UNITED STATES PATENT OFFICE.

MYRTLE WORKMAN, OF YORK, PENNSYLVANIA, ASSIGNOR OF ONE-HALF TO ROSS F. WORKMAN, OF YORK, PENNSYLVANIA.

SHOESTRING-FASTENER.

1,331,308.

Specification of Letters Patent. Patented Feb. 17, 1920.

Application filed June 28, 1919. Serial No. 307,365.

To all whom it may concern:

Be it known that I, MYRTLE WORKMAN, a citizen of the United States, residing at York, in the county of York, State of Pennsylvania, have invented certain new and useful Improvements in Shoestring-Fasteners, of which the following is a description, reference being had to the accompanying drawing and to the figures of reference 10 marked thereon.

This invention relates to new and useful improvements in shoe string fasteners, and more particularly to a fastener adapted to be invisibly attached to a shoe between the 15 upper and trimming members thereof, and capable of receiving the free end of the string tip.

The object of this invention is to provide a device adapted to be attached to the upper 20 portion of the shoe in such manner that it will not be noticeable and which will firmly hold the string tip in place, but will permit it to be disengaged therefrom by a slight pull.

25 In the drawings, which show by way of illustration one embodiment of the invention—

Figure 1 is an elevation of the inside of a shoe, showing the device in dotted lines 30 as applied thereto;

Fig. 2 is a view similar to Fig. 1, with the string tip in position;

Fig. 3 is a top plan view of the same;

Fig. 4 is a side elevation of a modification 35 of the device;

Fig. 5 is a view similar to Fig. 4 with the string tip in position;

Fig. 6 is a top plan view thereof;

Fig. 7 is a front and a side view of one 40 of the jaw members;

Figs. 8, 9 and 10 are separate views of a further modification, showing a single spring jaw coöperating with a stationary jaw.

45 In general, the invention comprises in one form, a device adapted to be attached to the shoe between the upper and trimming members thereof, and forming a pocket provided with an open end to receive the string tip.

50 Within this pocket is arranged a folded leaf spring, the projecting free ends of which

constitute the string retaining jaws. The folded portion thereof is adapted to contact with the side walls of the pocket, whereas the projecting jaws extend into the mouth of the pocket in position to receive the string tip. Means is also provided for guiding the tip directly between the spring jaws so that, when the string is inserted, it is held in the desired position until retracted 60 by a slight pull.

In another form, the invention consists of two thin pads of suitable elastic material arranged end to end and inclosed between the upper and trimming members of the shoe and provided with facings of metal or other suitable substance constituting jaws. The string when inserted between the metal facings or jaws will be firmly held by means of the elasticity of the pads. The facings 70 are flared outwardly at the top to permit the string tip to find easy entrance therebetween.

Referring now more particularly to Figs. 1 to 3 of the drawings, the invention, as 75 illustrated therein, includes a jaw retaining member or holder consisting of a flat plate 1, of metal or other suitable material of any desired shape, provided preferably at its central portion with a slight outstanding 80 bulge 2, forming a pocket to receive the spring retaining members. The interior walls of the plate forming this pocket are made parallel at the lower part 3 thereof, and are flared outwardly at the top or mouth 85 4 of the pocket. The pocket is adapted to be closed by a back plate 5 of suitable size and shape attached to the pocket plate in any suitable manner, as by rivets 6. It is apparent that the pocket plate and back 90 plate may be integral or may take various arrangements, all within the scope of the invention. Immediately at the mouth of the pocket there is provided a guide consisting of a tubular member 7, integral with 95 either plate, but in this instance preferably formed by cutting the metal of the back plate on each side of the mouth except at the center and then rolling or looping the cut sides thereof to provide the upstanding 100 tubular guide directly over the mouth of the pocket. Arranged within the pocket

is a resilient means for retaining the string tip, comprising a spring having a looped or folded portion 8, with preferably flat parallel sides at the lower portion thereof to fit within the parallel sides 3 of the pocket, so that it is held firmly in position. The free ends 9 of the looped portion of the spring constitute jaw retaining members and for this purpose the central portion of 10 the free ends is shaped inwardly, as at 10, so that the ends meet at a line passing longitudinally through the pocket. At their tips, the spring ends are preferably flared outwardly slightly to facilitate the entrance 15 of the strip tip therebetween.

Other arrangements of spring members may be resorted to for holding the string tip within the pocket, such as a plurality of springs or a single free spring end co-operating with a stationary jaw member. For instance, in Figs. 8, 9 and 10, there is shown a single plate 11 adapted to be held in any practical manner between the upper and trimming members of the shoe. This plate 20 is provided with an integral guide 12, formed as before, by slitting the plate and rolling the free ends together to form the tubular member. Suitably fastened within the tubular guide, as by soldering, spot welding or otherwise, is a single spring 13, the lower portion of which is bent inwardly across the axis of the guide into contact with the lower portion of the plate 11, so that the free end of the spring in conjunction 35 with the stationary plate forms a spring retaining member or jaws for the string tip.

The devices, as above described, are adapted to be fastened to the shoe in position between the upper and trimming members 40 thereof by means of rivets passing through the plates and the inner trimming members only as in Fig. 3. Obviously, other modes of attaching the device are within the scope of the invention.

45 In another form of the invention, there is arranged between the upper and lining members of the shoe, two abutting elastic pads 14 and 15, intermediate the opposing end faces 16 and 17 of which are adapted to be located the string retaining jaws or members 18 and 19. Each jaw or member consists of a narrow strip of metal or other suitable material provided with a series of integral protecting ears or flanges, as shown in Fig. 7. 50 These flanges project from the opposed faces of the strip, the guiding face thereof being provided with a single flange 20, arranged at the uppermost part thereof, whereas the opposed face is provided with a plurality of 55 flanges 21 projecting in the opposite direction and adapted to engage the sides of the elastic pad. The top and bottom ends of the strip are likewise provided with flanges 22 to engage the top and bottom edges of 60 the pad. By means of these latter flanges, 65

the strips are firmly anchored in position. In addition, the uppermost edge 23 of each strip and flange 22 are flared backwardly to enable the string tip to find easy entrance between these jaws when they are in opposed position. Obviously, any arrangement of 70 projecting flanges may be used, and, furthermore, it is apparent that other means may be availed of for attaching the jaws or members to the elastic pad, as at 24. If desired, 75 the ends of the pads, opposite the abutting faces, may be wedge shape to fit more compactly between the upper and lining members of the shoe.

When the jaw members are placed in position between the pads, the projecting flanges engage over the edges of the same to hold the jaws in opposition, the flaring ends of the jaws providing a guiding entrance for the string tip which is adapted to be held 80 between the jaws by means of the elasticity of the pads.

A device of the above character and attached as above described, produces a construction which does not in any way detract 85 from the appearance of the shoe and which will keep the bow or shoe string in place and prevent it from coming untied.

Having thus described my invention, what I claim as new and desire to secure by Letters Patent, is:

1. The combination of the upper and trimming members of a shoe, a string tip holder attached to at least one of said members and concealed between the upper edges of the same, said holder comprising two jaws adapted to receive the string tip therebetween, at least one of said jaws being yieldable.

2. The combination of the upper and trimming members of a shoe, a string tip holder attached to at least one of said members and concealed between the upper edges of the same, said holder comprising a jaw retaining member, a spring having a folded portion and projecting jaw portions; said folded portion adapted to engage the interior walls of said member, and said jaw portion being positioned to receive the string tip between the upper and trimming members.

3. The combination of the upper and trimming members of a shoe, a string tip holder attached to at least one of said members and concealed between the upper edges of the same, said holder comprising a jaw retaining member, a spring having a folded portion and projecting jaw portions, said folded portion adapted to engage the interior walls of said member, and means projecting between the edges of said upper and trimming members for directing a string tip between said projecting jaw portions.

4. A shoe string tip holder comprising in combination, the upper and trimming members of a shoe, of means concealed and ar-

ranged between said members at the upper edge thereof to receive the free tip of the shoe string after the same has been tied and to hold the same securely in position.

5 5. A shoe string tip holder comprising in combination, the upper and trimming members of a shoe, of concealed means providing

a string tip pocket between the upper edges of said members, said means being adapted to receive the free end of the string and to hold the same securely in position.

In testimony whereof, I affix my signature.

MYRTLE WORKMAN.
